UNITED STATES PATENT OFFICE

HYMAN KLIOT, OF BRONX, NEW YORK, ASSIGNOR TO CLIOT CLOSET MOTH PROOFER, INC.
OF NEW YORK, N. Y., A CORPORATION OF NEW YORK

DESIGN FOR A FACE PLATE FOR MOTH BALL CABINET

Application filed July 17, 1931. Serial No. 40,584. Term of patent 3½ years.

To all whom it may concern:

Be it known that I, HYMAN KLIOT, a citizen of Russia, residing at Bronx, county of Bronx, and State of New York, have invented a new, original, and ornamental Design for a Face Plate for Moth Ball Cabinet, of which the following is a specification, reference being had to the accompanying drawings, forming part thereof.

Figure 1 is a perspective view of the face plate for moth ball cabinet, showing my new design.

Figure 2 is a cross-sectional view of said face plate.

I claim:

The ornamental design for a face plate for moth ball cabinet, as shown.

HYMAN KLIOT.
